(57) **CLAIM**

The ornamental design for packaging label, as shown and described.

DESCRIPTION

FIG. 1 is a perspective view of a packaging label showing my new design;

FIG. 2 is a top plan view thereof;

FIG. 3 is a perspective view of a second embodiment thereof;

FIG. 4 is a top plan view thereof;

FIG. 5 is a perspective view of a third embodiment thereof;

FIG. 6 is a top plan view thereof;

FIG. 7 is a perspective view of a fourth embodiment thereof; and,

FIG. 8 is a top plan view thereof.

The dashed broken lines are directed to the environment and are for illustrative purposes only and form no part of the claimed design.

1 Claim, 4 Drawing Sheets
